UNITED STATES PATENT OFFICE.

GUSTAVE EMILE CHÉDRU, OF LEVALLOIS-PERRET, FRANCE.

PISTON.

1,220,070.

Specification of Letters Patent. Patented Mar. 20, 1917.

Application filed March 16, 1916. Serial No. 84,662.

To all whom it may concern:

Be it known that I, GUSTAVE EMILE CHÉDRU, a citizen of the French Republic, residing at Levallois-Perret, Seine, France, 5 have invented certain new and useful Improvements in Pistons, of which the following is a specification.

This invention relates to pistons, and more particularly to pistons for charging 10 pumps in two-stroke explosion engines.

The invention has for its object to make admission take place only when the piston has completed part of its suction stroke, and to avoid an excessive depression.

15 The invention comprises a piston formed in two sections, one of which constitutes the piston proper and is provided on its operative face with an annular groove such that a passage is formed between the piston and 20 the wall of the cylinder, the other section serving as a flap valve and being constituted by a ring engaging the operative face of the piston proper, so that it extends the said face to the wall of the cylinder.

25 In the accompanying drawing, by way of example, the single figure shows, in partial vertical axial section, the piston of the charging pump according to this invention.

The invention is illustrated, for example, 30 in connection with a two-stroke explosion engine with a charging pump of the kind described in an application filed in the names of Charles Maurice Philippe Montbarbon and myself, February 27, 1914, Serial No. 35 821,469, in which the charging pump is constituted by an annular body *a* inclosing the cylinder *b* of the engine along a portion of its length, a piston *c* independent of the piston *d* of the engine, a port *e* establishing 40 communication between the pump chamber and the engine cylinder, and a port *f* establishing communication between the source of fresh gas and the inner chamber of the pump, the said port *f* being uncovered by 45 the pump piston when it has accomplished a portion of its suction stroke. This invention obviates the disadvantage offered by such engines, that is to say, the infiltration of combustion gases into the pump body 50 owing to the strong depression produced in the said body by the pump piston when the latter, in effecting its suction stroke, has not yet uncovered the port *f* establishing communication between the pump chamber 55 and the source of fresh gases.

This is effected in the following manner:

An annular piston *c* is employed in the upper portion of the operative face of which is provided an annular recess *c*¹ so that the operative face does not come into contact 60 with the corresponding wall of the cylinder *a* in which it is mounted.

An annular part *g* is provided, fitting the cylinder *a* in which the said piston *c* is mounted, and of an inside diameter slightly 65 smaller than the diameter of the operative face of the piston. The said part is very thin near its central hole, and at its outer circumference, is so thick that it can be provided with one or more rings *g*¹. This 70 part is mounted on the piston with its inner flange resting on the operative face of the piston.

Thus the piston is provided with a sort of flap valve which, as soon as a depression is 75 produced in the pump chamber, will open and establish communication between the latter and the fresh gas inlet, long before the inlet port *f* for the said fresh gases is uncovered by the piston *c*; the said valve *g* 80 adhering, owing to its inertia, to the operative face of the piston when the latter begins its compression stroke, and becoming detached for the same reason, as soon as the said piston begins its suction stroke. This 85 result is more noticeable as the speed of working becomes greater.

The piston *c* may also have a spring *h* 90 calculated so that it normally keeps the part forming the valve, in engagement with the operative face of the piston, the said spring being preferably constituted by a ring provided with a certain number of branches in the form of a star, and maintained on the piston by means of an annular screw *h*¹ 95 screwed into the piston.

The valve *g* may also have a number of ribs *g*¹⁰ projecting from its inner wall and adapted to be used as guides for the said valve.

Obviously the invention is not limited to the construction described, but comprises any modifications within the scope of the claims.

What I claim as my invention and desire to secure by Letters Patent is:—

1. In a pump for the charging of two-stroke explosion engines, the combination, with a cylinder, of a piston working therein and comprising two sections, one of which forms the piston proper and is provided on its operative face with an annular groove

such that a passage is formed between the piston and the wall of the cylinder, the other section forming a flap valve and being constituted by a ring engaging the operative 5 face of the piston proper, so that it extends the said face to the wall of the cylinder.

2. In a charging pump, the combination with a cylinder; of a piston working therein and comprising two sections, one of which 10 forms the piston proper and is provided on its operative face with an annular groove such that a passage is formed between the piston and the wall of the cylinder, the other section forming a flap valve and being 15 constituted by a ring engaging the operative face of the piston proper, so that it extends the said face to said cylinder wall, and a spring for maintaining said flap valve in such engagement embodying a ring having a plurality of branches radiating therefrom and bearing against the flap valve.

3. In a charging pump, the combination with a cylinder; of a piston working therein and comprising two sections, one of 25 which forms the piston proper and is provided on its operative face with an annular groove such that a passage is formed between the piston and the wall of the cylinder, the other section forming a flap valve 30 and being constituted by an annular member having a packing ring at its periphery and 35 also having a plurality of guide ribs projecting from its inner wall.

4. In a charging pump, the combination with a cylinder; of a piston working therein and comprising two sections, one of 40 which forms the piston proper and is provided on its operative face with an annular groove such that a passage is formed between the piston and the wall of the cylinder, the other section forming a flap valve 45 and being constituted by an annular member engaging the operative face of the piston

proper, so that it extends the said face to said cylinder wall, said annular member having a packing ring at its periphery and also having a plurality of guide ribs projecting from its inner wall, and spring means for maintaining said annular member 50 in such engagement.

5. In a charging pump, the combination with a cylinder; of a piston working therein and comprising two sections, one of which forms the piston proper and is provided on its operative face with an annular groove such that a passage is formed between the piston and the wall of the cylinder, the other section forming a flap valve and being constituted by an annular member 55 engaging the operative face of the piston proper, so that it extends the said face to said cylinder wall, said annular member 60 having a packing ring at its periphery and also having a plurality of guide ribs projecting from its inner wall, and a spring for maintaining said flap valve in such engagement embodying a ring having a plurality of branches radiating therefrom and bearing against the flap valve.

6. In a charging pump, the combination with a cylinder; of a piston working therein and comprising two sections, one of 75 which forms the piston proper and is provided on its operative face with an annular groove such that a passage is formed between the piston and the wall of the cylinder, the other section forming a flap valve 80 and being constituted by a ring engaging the operative face of the piston proper, so that it extends the said face to said cylinder wall, and spring means for maintaining said flap valve in such engagement.

In testimony whereof I have signed my name to this specification in the presence of two subscribing witnesses.

GUSTAVE EMILE CHÉDRU.
